[57] CLAIM

The ornamental design for a game cabinet, as shown and described.

DESCRIPTION

FIG. 1 is a perspective view of a game cabinet employing my new design.

FIG. 2 is a front elevational view of the game cabinet shown in FIG. 1.

FIG. 3 is a left side elevational view of the game cabinet shown in FIG. 1.

FIG. 4 is a top plan view taken along the lines 4—4 of FIG. 2.

FIG. 5 is a top plan view showing the upper part of the game cabinet above the line 4—4 of FIG. 2.

FIG. 6 is a bottom plan view of the game cabinet shown in FIG. 1.

FIG. 7 is a rear elevational view of the game cabinet shown in FIG. 1.

The right side of the game cabinet is a mirror image of the left side.
